Manny L. Weiss, Queens, N. Y.

Application August 10, 1954, Serial No. 448,943

16 Claims. (Cl. 220—19)

This invention relates to racks of the type commonly employed in washing a plurality of drinking glasses or the like.

It is an object of the present invention to provide a rack for washing drinking glasses or the like comprising a basket member in which the drinking glasses are supported in spaced relationship to each other, and a removable cover which will permit the rack to be inverted while retaining the drinking glasses therein and permitting the latter to drain.

It is another object of the present invention to provide a rack for washing drinking glasses of the above type wherein the cover is provided with a pair of oppositely disposed handles, said handles being adapted upon pivotal movement thereof to lock the cover to the basket when said handles are in the operative position.

Other objects of the present invention are to provide a rack for washing drinking glasses or the like bearing the above objects in mind which is of simple construction, inexpensive to manufacture, has a minimum number of parts, is easy to use and efficient in operation.

For other objects and a better understanding of the invention reference may be had to the following detailed description taken in connection with the accompanying drawing, in which:

Figure 1 is a top plan view of a preferred embodiment of the invention and showing the handles in operative position for holding the rack and for locking the cover to the basket portion;

Figure 2 is a perspective view of the rack showing the handles in the operative position with the rack being inverted so as to permit the glasses to drain;

Figure 3 is an exploded perspective view of the cover and basket and showing the handles in their inoperative position;

Figure 4 is a fragmentary vertical sectional view taken along the line 4—4 of Figure 2;

Figure 5 is an enlarged perspective view of one of the handles;

Figure 6 is an exploded perspective view of the parts forming the basket and showing in phantom a drinking glass positioned therewithin;

Figure 7 is a vertical sectional view taken along the line 7—7 of Figure 1;

Figure 8 is a view similar to Figure 7 but showing the rack employed with a drinking glass of less height than the drinking glass of Figure 7;

Figure 9 is a top plan view of the cover member of a still further modified form of the invention;

Figure 10 is a front elevational view thereof but showing both handles in their operative position;

Figure 11 is a side elevational view thereof looking from the right of Figure 10;

Figure 12 is a perspective view of one of the handles;

Figure 13 is a top plan view of a modified form of the basket member adapted to be employed with the modified cover of Figures 9—12;

2

Figure 14 is a side elevational view thereof looking from the right of Figure 13;

Figure 15 is a fragmentary perspective view of one of the corners of the basket of Figures 13 and 14;

5 Figure 16 is a fragmentary top plan view of the modified form of the invention of Figures 9—15 showing the drinking glasses in position therewithin and the handles in the operative, locking position, and

10 Figure 17 is a fragmentary vertical sectional view taken along the line 17—17 of Figure 16.

Referring now more in detail to the drawing wherein similar reference numerals identify corresponding parts throughout the several views, 10 indicates generally a rack for washing drinking glasses or the like including a basket portion indicated generally at 11 (Figure 3) and a cover portion indicated generally at 12, substantially as illustrated.

The basket 11 includes a lower endless loop of wire 13 of substantially square configuration having rounded corners and connected in vertically spaced relationship to an intermediate endless loop 14 and an upper endless loop 15 of identical size and shape as the lower loop 13 by means of the corner posts 16, the corner posts 16 being suitably welded to the insides of the loops 13, 14 and 15.

20 25 The loops 13, 14 and 15 are further secured together intermediate their corners by means of the braces 17 of inverted U-shaped configuration, the braces 17 being suitably welded to the insides of the loops. It will be noted that two such braces 17 are provided for each side of the basket and that two pairs of oppositely disposed braces 17 are connected by the horizontal wires 18 intermediate the loops 13 and 14 and intermediate the loops 14 and 15.

30 35 As shown in Figure 6, a pair of opposite sides of the lower loop 13 of the basket are connected by parallel, closely spaced wires 19 welded at their opposite ends to the top of the loop 13. Parallel, widely spaced wires 20 disposed at substantially right angles to the wires 19 are welded across the tops of the latter, extending to the other opposite sides of the loop 13 of the basket and cooperating with wires 19 to provide a closely spaced grill supporting the bottoms of the drinking glasses 21.

40 45 50 Parallel, widely spaced wires 22 connect a pair of opposite sides of intermediate loop 14, the ends of wires 22 being welded to the underside of the loop 14. Second parallel, widely spaced wires 23 disposed at substantially right angles to the wires 22 connect the other opposite sides of loop 14, the ends of the wires 23 being welded to the underside of the loop 14 and to the top sides of the wires 22 and forming thereby a widely spaced grill adapted to receive downwardly therethrough the drinking glasses 21 in spaced relationship to each other.

55 60 Parallel, widely spaced wires 24 connect a pair of opposite sides of the upper loop 15, the ends of the wires 24 being welded to the underside of the loop with the wires 24 aligned vertically with the wires 23 of the intermediate loop. Second parallel, widely spaced wires 25 connect the other opposite sides of the loop 15, the ends of the wires 25 being welded to the underside of the loop 15, the wires 25 passing under the wires 24 and being welded thereto to form a widely spaced grill receiving the drinking glasses 21 downwardly therethrough in spaced relationship, the wires 25 being aligned vertically with the wires 22.

65 The basket 11 is adapted to support thereon a plurality of the drinking glasses 21, retaining the latter in spaced relationship to each other.

70 The cover 12 includes a lower endless loop of wire 26 of substantially square configuration and having rounded corners, the lower loop 26 being connected in vertically spaced relationship to an intermediate loop 27 and an upward loop 28 by means of the posts 29, the posts 29 being welded to the insides of the loops 26, 27

and 23. It will be noted that two posts 29 are provided for each side of the cover, the posts 29 being displaced from the corners of the cover.

One pair of opposite sides of the upper loop 28 are connected by parallel, widely spaced wires 30, the opposite ends of the wires 30 being welded to the top of the loop 28. The wires 30 are aligned vertically with the wires 25 of the basket member. One of the wires 30a is integrally formed at its ends with the depending vertical posts 31, the posts 31 extending downwardly at right angles to the wire 30a and being welded to the outside of the intermediate loop 27 and the lower loop 26.

A pair of oppositely disposed handles are pivotally mounted on each of the posts 31 intermediate the intermediate loop 27 and the lower loop 26 and are indicated generally at 32 (Figure 5). Each of the handles 32 is formed from a unitary length wire and includes an outer end 33 formed at right angles thereto with the sides 34. Each of the sides 34 is formed with a loop 35 with the free inner ends thereof being looped twice about the post 31, as at 36, being then doubled back and extending parallel to the sides 34, as at 37, and terminating in loops 38 substantially parallel to the loops 35.

A bushing 39 sleeves each of the posts 31 intermediate the looped portions 36 of the handles 32.

The loops 26, 27 and 28 of the cover 12 are slightly larger than the loops 13, 14 and 15 of the basket 11, permitting the cover 12 to be slipped downwardly onto the basket in nesting relationship thereto as shown in Figures 1, 2 and 7, with the wires 30 resting on the open upper ends of the drinking glasses 21. The cover 12 is placed downwardly onto the basket 11 with the handles 32 in the open position of Figure 3 and disposed adjacent the horizontal wires 18 of the basket. The handles 32 are then rotated in the direction of the arrows of Figure 3 to the parallel positions of Figure 1, which movement causes the lowermost loops 35 and 38 to snap into locking position intermediate the upper loop 15 and the uppermost brace of wire 18, as shown in Figure 7. It will be noted that the ends 33 of the handle 32 extend beyond one side of the rack 10 (Figure 10) permitting the same to be grasped in both hands when dipping the rack and glasses into a cleaning solution or the like. By this construction the rack 10 may also be inverted (Figure 2) to permit the glasses to drain. Thus the handles 32 not only permit the rack 10 to be manipulated in a convenient manner, but also serve to lock the cover 12 to the basket 11 and permit the rack to be inverted without dropping the drinking glasses.

As shown in Figure 8, the rack 10 may also be employed with drinking glasses 21a of less height than the drinking glasses 21, in which case the wires 30 of the cover 12 will rest directly on the upper loop 15 of the basket 11, and both the upper and lower loops 35 and 38 of the locking handles 32 being snapped intermediate the lower loop 13, the lowermost wire 18 and the intermediate loop 14.

Referring now particularly to Figures 9-17, there is shown a modified form of the present invention indicated generally at 40 and including a basket indicated generally at 41 and a removable cover therefore indicated generally at 42, substantially as illustrated.

The basket 41 includes a lower endless loop of wire 43 of substantially square configuration and provided with rounded corners, the lower loop 43 being connected in vertically spaced relationship to an intermediate loop 44 and an upper loop 45, both identical in size and shape with the lower loop 43, by means of the posts 46. It will be noted that the posts 46 are welded to the insides of the loops 43, 44 and 45, one pair of oppositely disposed sides of the basket 41 being provided with four posts 46 while the other pair of oppositely disposed sides thereof are provided with three posts 46.

The loops 43, 44 and 45 are further connected to each

other at their corners by means of the corner posts 47 of inverted U-shaped configuration, the sides of the posts 47 tapering downwardly and coming together at their lower ends while the upper looped portions thereof are bent inwardly, substantially as illustrated.

5 A pair of opposite sides of the lower loop 43 are connected by the parallel, closely spaced wires 48, the opposite ends of the wires 48 being welded to the upper side of the loop 43. Second parallel, widely spaced wires 49 (Figure 15) connect the other opposite sides of loop 43, the opposite ends of the wires 49 being welded to the underside of loop 43, the wires 49 passing under the wires 48 and being welded thereto. Thus the wires 48 and 49 form a closely spaced latticework design to support the lower ends of the drinking glasses 21.

10 A pair of opposite sides of the intermediate loop 44 are connected by the parallel, widely spaced wires 50 (Figure 17), the opposite ends of the wires 50 being welded to the underside of the loop 44. The other opposite sides of the loop 44 are connected by second parallel, widely spaced wires 51, the opposite ends of the wires 51 being welded to the underside of the loop 44. The wires 51 pass under the wires 50 and are welded thereto, the wires 50 and 51 forming a widely spaced latticework adapted to receive the drinking glasses 21 therethrough in spaced relationship to each other.

15 Opposite sides of the upper loop 45 are connected by parallel, widely spaced wires 53, opposite ends of the wires 53 being welded to the underside of loop 45. Second parallel, widely spaced wires 54 connect the other opposite sides of the loop 45, the opposite ends of the wires 54 being welded to the underside of the loop 45. The wires 54 pass under the wires 53, being welded thereto, and forming therewith a widely spaced latticework adapted to receive the drinking glasses 21 downwardly therethrough in freely spaced relationship to each other. The latticework of the upper loop 45 is, of course, aligned vertically with the latticework of the intermediate loop 44.

20 The sides of the basket 41 having four posts 46 are provided with horizontal wires 54, the opposite ends of the wires 54 being welded to the innermost pair of posts 46. It will be noted that a first pair of wires 54 is disposed intermediate the lower loop 43 and intermediate loop 44, and a second pair intermediate loop 44 and upper loop 45.

25 The cover 42 includes a lower endless loop of wire 55 of substantially square configuration and having rounded corners, the lower loop 55 being connected in vertically spaced relationship to an intermediate loop 56 and upper loop 57, both identical in size and shape with the lower loop 55, by means of the posts 58. The posts 58, it will be noted, are welded to the outsides of the loops 55, 56 and 57.

30 Opposite sides of the upper loop 57 are connected by parallel, widely spaced wires 59, the opposite ends of the wires 59 being welded to the upper side of the loop 57.

35 As shown in Figure 12, the intermediate loop 56 on a pair of opposite sides thereof is provided with laterally aligned loop formations 60, while the lower loop 55 is provided with loop formations 61 aligned vertically with the loop formations 60. A pin 62 is rotatably mounted within each of the vertically aligned loops 60, 61, the upper and lower ends of the pins 62 being peened, as at 63 and 64, whereby to prevent displacement of the pins through the loops in an obvious manner.

40 A pair of handles indicated generally at 65 are pivotally mounted on each of the pins 62. Each of the handles 65 includes an outer vertical end portion 66 connected at its lower end to a horizontal side portion 67 and at its upper end to a horizontal side portion 68, the inner end of the upper side portion 68 being formed with a vertical portion 69 which is in turn formed at its lower end with an upper side portion 70, substantially as illustrated in Figure 12. The upper side portion 70

and the lower side portion 67 are formed with inwardly extending, vertically aligned loops 71 and 72, respectively. The inner ends of the side portions 67 and 70 are looped twice around the pin 62, as at 73 and 74, respectively. The upper side portion 70 is formed with a doubled up portion 75 which terminates in a loop 76, while the lower side portion 67 is formed with the doubled up portion 77 which terminates in a loop 78, the loops 76 and 78 being aligned vertically and extending inwardly in a manner similar to the loops 71 and 72.

A bushing 79 sleeves each of the pins 62 intermediate loop portions 73 and 74.

The loops 55, 56 and 57 of the cover 42 are slightly larger than the loops 43, 44 and 45 of the basket 41, permitting the cover to fit downwardly onto the basket, as shown in Figure 17. The struts 59 of the cover will rest on the upper edge of the glasses 21 when the latter is of greater height than the basket. The cover 42 is placed on the basket 41 so that the handles 65 are adjacent the struts 54. When the handles 65 are rotated inwardly, the loops 71, 76 thereof will snap intermediate (Figure 7) the uppermost pair of struts 57 while the loops 72, 78 thereof will snap intermediate the intermediate loops 44 and the strut 54 directly therebelow whereby to lock the cover to the basket. The enlarged ends of the handle 65 formed by the portions 67, 65, 68 and 69 will provide a convenient means for holding the rack when it is dipped into the washing solution and inverted after removal to permit the drinking glasses 21 to drain.

In other respects the use and operation of the rack 42 is similar to the rack 10 previously described.

While various changes may be made in the detailed construction it should be understood that such changes shall be within the spirit and scope of the appended claims.

I claim:

1. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, each of said handle means being formed from a unitary length of wire and including an outer substantially vertical end, vertically spaced horizontal sides, said vertically spaced sides being formed with inwardly extending, vertically aligned loops, substantially vertical posts on opposite sides of said cover means, the inner ends of said vertically spaced sides being looped around said posts and being formed with second inwardly extending vertically aligned loops, and a plurality of substantially horizontal, vertically spaced wires on opposite sides of said basket means, said loops being adapted to snap intermediate a selected pair of said vertically spaced wires whereby to lock said cover means to said basket means, said end portions of said handle means extending beyond the rack when said handle means are in their locked positions.

2. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, each of said handle means being formed from a unitary length of wire and including an outer substantially vertical end, vertically spaced horizontal sides, said vertically spaced sides being formed with inwardly extending, vertically aligned loops, sub-

stantially vertical posts on opposite sides of said cover means, the inner ends of said vertically spaced sides being looped around said posts and being formed with second inwardly extending vertically aligned loops, and a plurality of substantially horizontal, vertically spaced wires on opposite sides of said basket means, said loops being adapted to snap intermediate a selected pair of said vertically spaced wires whereby to lock said cover means to said basket means, said end portions of said handle means extending beyond the rack when said handle means are in their locked positions, each of said handle means being formed with a vertically enlarged outer portion to facilitate gripping thereof.

3. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, each of said handle means being formed from a unitary length of wire and including an outer substantially vertical end, vertically spaced horizontal sides, said vertically spaced sides being formed with inwardly extending, vertically aligned loops, substantially vertical posts on opposite sides of said cover means, the inner ends of said vertically spaced sides being looped around said posts and being formed with second inwardly extending vertically aligned loops, and a plurality of substantially horizontal, vertically spaced wires on opposite sides of said basket means, said loops being adapted to snap intermediate a selected pair of said vertically spaced wires whereby to lock said cover means to said basket means, said end portions of said handle means extending beyond the rack when said handle means are in their locked positions, and a bushing sleeving each of said vertical posts intermediate the looped inner ends of said vertically spaced sides.

4. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, each of said handle means being formed from a unitary length of wire and including an outer substantially vertical end, vertically spaced horizontal sides, said vertically spaced sides being formed with inwardly extending, vertically aligned loops, substantially vertical posts on opposite sides of said cover means, the inner ends of said vertically spaced sides being looped around said posts and being formed with second inwardly extending vertically aligned loops, and a plurality of substantially horizontal, vertically spaced wires on opposite sides of said basket means, said loops being adapted to snap intermediate a selected pair of said vertically spaced wires whereby to lock said cover means to said basket means, said end portions of said handle means extending beyond the rack when said handle means are in their locked positions, each of said handle means being formed with a vertically enlarged outer portion to facilitate gripping thereof, and a bushing sleeving each of said posts intermediate the inner looped ends of said vertically spaced sides.

5. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted

handle means on opposite sides of said cover means adapted to be rotated against said cover and basket means, said handle means adapted to lock said cover means to said basket means, said cover means comprising a lower endless loop wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop.

6. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, one of said spaced wires at opposite ends thereof being formed with vertical posts secured to the outside of said lower, intermediate and upper loops, each of said handle means being mounted on one of said posts intermediate said lower and intermediate loops.

7. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower endless loop of substantially rectangular configuration adapted to fit within said cover loops, an intermediate loop, and an upper loop, said intermediate and upper loops being identical in size and shape with said basket lower loop, substantially vertical corner posts connecting said lower, intermediate and upper basket loops to each other in vertically spaced relationship, substantially inverted U-shaped loops connecting said lower, intermediate and upper basket loops intermediate said corner posts, and horizontal, vertical spaced struts connecting an innermost oppositely disposed pair of said inverted U-shaped loops, each of said handle means including vertically spaced, vertically aligned, inwardly extending projections adapted to be snapped intermediate a selected pair of said horizontal wires.

8. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means

adapted to be rotated against said cover and basket means, said handle means adapted to lock said cover means to said basket means, said cover means comprising a lower endless loop wire of substantially rectangular configuration, an intermediate loop, and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower endless loop of substantially rectangular configuration adapted to fit within said cover loops, an intermediate loop, and an upper loop, said intermediate and upper loops being identical in size and shape with said basket lower loop, substantially vertical corner posts connecting said lower, intermediate and upper basket loops to each other in vertically spaced relationship, substantially inverted U-shaped loops connecting said lower, intermediate and upper basket loops intermediate said corner posts, and horizontal, vertical spaced struts connecting an innermost oppositely disposed pair of said inverted U-shaped loops, each of said handle means including vertically spaced, vertically aligned, inwardly extending projections adapted to be snapped intermediate a selected pair of said horizontal wires, a plurality of substantially parallel, closely spaced wires connecting a pair of opposite sides of said basket lower loop, and second parallel, widely spaced wires connecting the other opposite sides of said lower basket loop at substantially right angles to said first wires and providing therewith a closely spaced latticework adapted to support thereon the bottoms of the drinking glasses.

9. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower endless loop of substantially rectangular configuration adapted to fit within said cover loops, an intermediate loop and an upper loop, said intermediate and upper loops being identical in size and shape with said basket lower loop, substantially vertical corner posts connecting said lower, intermediate and upper basket loops to each other in vertically spaced relationship, substantially inverted U-shaped loops connecting said lower, intermediate and upper basket loops intermediate said corner posts, and horizontal, vertical spaced struts connecting an innermost oppositely disposed pair of said inverted U-shaped loops, each of said handle means including vertically spaced, vertically aligned, inwardly extending projections adapted to be snapped intermediate a selected pair of said horizontal wires, a plurality of substantially parallel, closely spaced wires connecting a pair of opposite sides of said basket lower loop, and second parallel, widely spaced wires connecting the other opposite sides of said lower basket loop at substantially right angles to said first wires and providing therewith a closely spaced latticework adapted to support thereon the bottoms of the drinking glasses, third parallel, widely spaced wires connecting a pair of opposite sides of said intermediate basket loop, and fourth, widely spaced wires

connecting the other opposite sides of said intermediate basket loop and forming with said third wires a widely spaced latticework adapted to receive downwardly therethrough the drinking glasses in freely spaced relationship to each other.

10. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower endless loop of substantially rectangular configuration adapted to fit within said cover loops, an intermediate loop and an upper loop, said intermediate and upper loops being identical in size and shape with said basket lower loop, substantially vertical corner posts connecting said lower, intermediate and upper basket loops to each other in vertically spaced relationship, substantially inverted U-shaped loops connecting said lower, intermediate and upper basket loops intermediate said corner posts, and horizontal, vertical spaced struts connecting an innermost oppositely disposed pair of said inverted U-shaped loops, each of said handle means including vertically spaced, vertically aligned, inwardly extending projections adapted to be snapped intermediate a selected pair of said horizontal wires, a plurality of substantially parallel, closely spaced wires connecting a pair of opposite sides of said basket lower loop, and second parallel, widely spaced wires connecting the other opposite sides of said lower basket loop at substantially right angles to said first wires and providing therewith a closely spaced latticework adapted to support thereon the bottoms of the drinking glasses, third parallel, widely spaced wires connecting a pair of opposite sides of said intermediate basket loop, and fourth parallel, widely spaced wires connecting the other opposite sides of said intermediate basket loop and forming with said third wires a widely spaced latticework adapted to receive downwardly therethrough the drinking glasses in freely spaced relationship to each other, fifth parallel, widely spaced wires connecting a pair of opposite sides of said upper basket loop, and sixth parallel, widely spaced wires connecting the other opposite sides of said upper basket loop and providing with said fifth wires a widely spaced latticework aligned with said intermediate loop latticework and adapted to receive the drinking glasses downwardly therethrough in freely spaced relationship to each other.

11. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substan-

tially parallel, spaced wires connected at opposite ends to a pair of opposite sides of said upper loop, said basket means comprising a lower endless loop of substantially rectangular configuration, an intermediate endless loop

5 and an upper endless loop, said intermediate and upper loops being identical in size and shape with said lower basket loop, side posts connecting said lower, intermediate and upper basket loops in spaced relationship to each other, corner posts further connecting said lower, intermediate and upper basket loops to each other, each of said corner posts being of substantially inverted U-shaped configuration having the sides thereof converging to said lower basket loop and having their upper looped ends bent inwardly, and substantially horizontal, vertically spaced wires connecting the innermost pairs of said side posts on oppositely disposed sides of said basket, each of said handle means including inwardly extending, vertically spaced projections adapted to be snapped intermediate a selected pair of said horizontal wires.

15 12. An article of the class described comprising basket means open at the top and adapted to support therewithin in spaced relationship a plurality of drinking glasses or the like, cover means adapted to fit downwardly onto said basket means and adapted to retain the drinking glasses

20 within said basket, and a pair of pivotally mounted handle means on opposite sides of said cover means adapted to be rotated against said cover and basket means, said handle means adapted to lock said cover means to said basket means, said cover means comprising a lower endless loop

25 wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower

30 endless loop of substantially rectangular configuration, an intermediate endless loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower

35 endless loop of substantially rectangular configuration, an intermediate endless loop and an upper endless loop, said intermediate and upper loops being identical in size and shape with said lower basket loop, side posts connecting said lower, intermediate and upper basket loops in spaced relationship to each other, corner posts further connecting said lower, intermediate and upper basket loops to each other, each of said corner posts being of substantially inverted U-shaped configuration having the sides thereof converging to said lower basket loop and having their upper looped ends bent inwardly, and substantially horizontal, vertically spaced wires connect-

40 ing the innermost pairs of said side posts on oppositely disposed sides of said basket, each of said handle means including inwardly extending, vertically spaced projections adapted to be snapped intermediate a selected pair of said horizontal wires, first parallel, closely spaced wires

45 connecting a pair of opposite sides of said lower basket loop, and second parallel, widely spaced wires connecting the other opposite sides of said lower basket loop and forming with said first wires a latticework adapted to support thereon the bottoms of the drinking glasses or

50 the like.

13. An article of the class described comprising basket means open at the top and adapted to support therewithin in spaced relationship a plurality of drinking glasses or the like, cover means adapted to fit downwardly onto

55 said basket means and adapted to retain the drinking glasses within said basket, and a pair of pivotally mounted handle means on opposite sides of said cover means adapted to be rotated against said cover and basket means, said handle means adapted to lock said cover

60 means to said basket means, said cover means comprising a lower endless loop wire of substantially rectangular configuration, an intermediate loop, and an upper endless loop, said intermediate and upper loops being identical in size and shape with said lower loop, vertical

65 posts connecting said lower, intermediate and upper loops

70

75

in vertically spaced relationship to each other and substantially parallel, spaced wires connected at opposite ends to a pair of opposite sides of said upper loop, said basket means comprising a lower endless loop of substantially rectangular configuration, an intermediate endless loop and an upper endless loop, said intermediate and upper loops being identical in size and shape with said lower basket loop, side posts connecting said lower, intermediate and upper basket loops in spaced relationship to each other, corner posts further connecting said lower, intermediate and upper basket loops to each other, each of said corner posts being of substantially inverted U-shaped configuration having the sides thereof converging to said lower basket loop and having their upper looped ends bent inwardly, and substantially horizontal, vertically spaced wires connecting the innermost pairs of said side posts on oppositely disposed sides of said basket, each of said handle means including inwardly extending, vertically spaced projections adapted to be snapped intermediate a selected pair of said horizontal wires, first parallel, closely spaced wires connecting a pair of opposite sides of said lower basket loop, and second parallel, widely spaced wires connecting the other opposite sides of said lower basket loop and forming with said first wires a latticework adapted to support thereon the bottoms of the drinking glasses or the like, third parallel, widely spaced wires connecting a pair of opposite sides of said intermediate basket loop, and fourth parallel, widely spaced wires connecting the other opposite sides of said intermediate basket loop and forming with said third wires a widely spaced latticework adapted to receive downwardly therethrough the drinking glasses in freely spaced relationship to each other.

14. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop, and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower endless loop of substantially rectangular configuration, an intermediate endless loop, and an upper endless loop, said intermediate and upper loops being identical in size and shape with said lower basket loop, side posts connecting said lower, intermediate and upper basket loops in spaced relationship to each other, corner posts further connecting said lower, intermediate and upper basket loops to each other, each of said corner posts being of substantially inverted U-shaped configuration having the sides thereof converging to said lower basket loop and having their upper looped ends bent inwardly, and substantially horizontal, vertically spaced wires connecting the innermost pairs of said side posts on oppositely disposed sides of said basket, each of said handle means including inwardly extending, vertically spaced projections adapted to be snapped intermediate a selected pair of said horizontal wires, first parallel, closely spaced wires connecting a pair of opposite sides of said lower basket loop, and second parallel, widely spaced wires connecting the other opposite sides of said lower basket loop and forming with said first wires a latticework adapted to support thereon the bottoms of the drinking glasses or the like, third parallel, widely spaced wires connecting a pair of opposite sides of said intermediate basket loop, and fourth parallel, widely spaced wires connecting the other opposite sides of said intermediate basket loop and forming with said third wires a widely spaced latticework adapted to receive downwardly therethrough the drinking glasses in freely spaced relationship to each other, fifth parallel, widely spaced wires connecting a pair of opposite sides of said upper basket loop, and sixth parallel, widely spaced wires connecting the other opposite sides of said upper basket loop and forming with said fifth wires a widely spaced latticework adapted to receive downwardly therethrough a drinking glass or the like, said upper loop latticework being aligned vertically with said intermediate loop latticework.

fourth parallel, widely spaced wires connecting the other opposite sides of said intermediate basket loop and forming with said third wires a widely spaced latticework adapted to receive downwardly therethrough the drinking glasses in freely spaced relationship to each other, fifth parallel, widely spaced wires connecting a pair of opposite sides of said upper basket loop, and sixth parallel, widely spaced wires connecting the other opposite sides of said upper basket loop and forming with said fifth wires a widely spaced latticework adapted to receive downwardly therethrough a drinking glass or the like, said upper loop latticework being aligned vertically with said intermediate loop latticework.

15. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop, and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower endless loop of substantially rectangular configuration, an intermediate endless loop, and an upper endless loop, said intermediate and upper loops being identical in size and shape with said lower basket loop, side posts connecting said lower, intermediate and upper basket loops in spaced relationship to each other, corner posts further connecting said lower, intermediate and upper basket loops to each other, each of said corner posts being of substantially inverted U-shaped configuration having the sides thereof converging to said lower basket loop and having their upper looped ends bent inwardly, and substantially horizontal, vertically spaced wires connecting the innermost pairs of said side posts on oppositely disposed sides of said basket, each of said handle means including inwardly extending, vertically spaced projections adapted to be snapped intermediate a selected pair of said horizontal wires, first parallel, closely spaced wires connecting a pair of opposite sides of said lower basket loop, and second parallel, widely spaced wires connecting the other opposite sides of said lower basket loop and forming with said first wires a latticework adapted to support thereon the bottoms of the drinking glasses or the like, third parallel, widely spaced wires connecting a pair of opposite sides of said intermediate basket loop, and fourth parallel, widely spaced wires connecting the other opposite sides of said intermediate basket loop and forming with said third wires a widely spaced latticework adapted to receive downwardly therethrough the drinking glasses in freely spaced relationship to each other, fifth parallel, widely spaced wires connecting a pair of opposite sides of said upper basket loop, and sixth parallel, widely spaced wires connecting the other opposite sides of said upper basket loop and forming with said fifth wires a widely spaced latticework adapted to receive downwardly therethrough a drinking glass or the like, said upper loop latticework being aligned vertically with said intermediate loop latticework, said lower and intermediate basket loops on a pair of oppositely disposed sides thereof being provided with vertically aligned loop formations, vertical pins rotatably mounted within said vertically aligned loop formations, each of said handle means comprising a unitary length of wire having vertically spaced, horizontal side portions, said side portions being formed

with vertically aligned, inwardly extending loops, the inner ends of said side portions being looped around said pins and being formed with second inwardly extending, vertically aligned loops, said first and second vertically aligned loops being adapted to snap intermediate vertically spaced pairs of said horizontal wires provided on opposite sides of said basket means and sleeve means on each of said pins intermediate the looped inner ends of said side portions.

16. An article of the class described comprising basket means open at the top and adapted to support therewithin in spaced relationship a plurality of drinking glasses or the like, cover means adapted to fit downwardly onto said basket means and adapted to retain the drinking glasses within said basket, and a pair of 10 pivotally mounted handle means on opposite sides of said cover means adapted to be rotated against said cover and basket means, said handle means adapted to lock said cover means to said basket means, said cover means comprising a lower endless loop wire of substantially rectangular configuration, an intermediate loop and an upper endless loop, said intermediate and upper loops being identical in size and shape with said lower loop, vertical posts connecting said lower, intermediate and upper loops in vertically spaced relationship to each other and substantially parallel, spaced wires connected at opposite ends to a pair of opposite sides of said upper loop, said basket means comprising a lower endless loop of substantially rectangular configuration, an intermediate endless loop and an upper endless loop, said intermediate and upper loops being identical in size and shape with said lower basket loop, side posts connecting said lower, intermediate and upper basket loops in spaced relationship to each other, corner posts further connecting said lower, intermediate and upper basket loops to each other, each of said corner posts being of substantially inverted U-shaped configuration having the sides thereof converging to said lower basket loop and having their upper looped ends bent inwardly, and substantially horizontal, vertically spaced wires connecting the innermost pairs of 40 said side posts on oppositely disposed sides of said basket, each of said handle means including inwardly extending, vertically spaced projections adapted to be snapped intermediate a selected pair of said horizontal wires, first parallel, closely spaced wires connecting a pair of opposite sides of said lower basket loop, and second parallel, 45 widely spaced wires connecting the other opposite sides

5 of said lower basket loop and forming with said first wires a latticework adapted to support thereon the bottoms of the drinking glasses or the like, third parallel, widely spaced wires connecting a pair of opposite sides of said intermediate basket loop, and fourth parallel, widely spaced wires connecting the other opposite sides of said intermediate basket loop and forming with said third wires a widely spaced latticework adapted to receive downwardly therethrough the drinking glasses in freely spaced relationship to each other, fifth parallel, widely spaced wires connecting a pair of opposite sides of said upper basket loop, and sixth parallel, widely spaced wires connecting the other opposite sides of said upper basket loop and forming with said fifth wires a widely spaced latticework adapted to receive downwardly therethrough a drinking glass or the like, said upper loop latticework being aligned vertically with said intermediate loop latticework, said lower and intermediate basket loops on a pair of oppositely disposed sides thereof being provided with vertically aligned loop formations, vertical pins rotatably mounted within said vertically aligned loop formations, each of said handle means comprising a unitary length of wire having vertically spaced, horizontal side portions, said side portions being formed with vertically aligned, inwardly extending loops, the inner ends of said side portions being looped around said pins and being formed with second inwardly extending, vertically aligned loops, said first and second vertically aligned loops being adapted to snap intermediate vertically spaced pairs of said horizontal wires provided on opposite sides of said basket means and sleeve means on each of said pins intermediate the looped inner ends of said side portions, said handle means including vertically enlarged outer ends extending beyond the sides of the racks when said handle means are locked thereagainst whereby to facilitate handling of the rack.
